UNITED STATES PATENT OFFICE.

WILLIAM S. WESTON, OF CHICAGO, ILLINOIS.

RAILWAY-TIE PLATE.

No. 914,093.

Specification of Letters Patent. Patented March 2, 1908.

Application filed July 24, 1908. Serial No. 445,075.

To all whom it may concern:

Be it known that I, WILLIAM S. WESTON, a citizen of the United States, and a resident of Chicago, county of Cook, and State of Illinois, have invented new and useful Improvements in Railway-Tie Plates, of which the following are full, clear, and exact specifications.

My invention relates to improvements in railway tie plates of the class that are interposed between the base of the rail and the tie, stringer, or other substructure on which the rail is thereby better held and supported; and has for its object the provision of new and improved means integral with the tie plate for preventing the longitudinal movement or "creeping" of the rail over the plate and substructure. I attain this object by means of a tie plate provided with oppositely disposed shoulder formations adapted to grip the edges of the rail base when the rail is seated; and my present invention is distinguished from my prior invention of a similar device illustrated, described and claimed in application filed December 30, 1907, Serial No. 408,542, by the novel means employed to cause the plate to grip the rail base. This novel feature is clearly illustrated in the accompanying drawings which form a part of this specification, and is particularly pointed out in the claims.

In the drawings, Figure 1 is an edge view of the plate showing a section of the rail seated on the plate and attached to the tie by means of screw spikes passed through the plate; Fig. 2 is a plan view of the plate showing in full lines the relative positions of the two shoulders when the plate is free from the rail, and showing by dotted lines the position of one shoulder relative to the opposite shoulder; when the distance between them is expanded sufficient to permit the rail to be seated between them; Fig. 3 is a large scale, vertical cross section of the plate on the line 3—3 of Figs. 1 and 2.

The same numerals refer to the same or similar parts in the several views.

The tie plate is designated by the numeral 2, the rail by 3, the tie by 4 and the spikes by 5. The tie-plate is formed of resilient, wrought iron or steel and is of such shape that it can be readily formed from rolled bars that are cut into sections to form the individual plates. Two shoulders 6, 6 are formed on the upper surface of the tie plate so as to provide a seat for the rail between

them. When the plate is free from the rail the distance between the shoulders or the width of the seating space is slightly less than the width of the rail base. The central portion of the plate beneath the rail at 7 is preferably rolled thin to form a space 8 beneath the rail and allow the rail to take its bearing on the thicker portions 9, 9 adjacent the shoulders. The thin portion of the plate 7, Fig. 2, is divided by a series of cuts or oblong openings 10, 10, into a series of metal strips 11, 11, connecting the two ends of the plate which carry the shoulders. These metallic connecting strips are formed in a diagonal position at an angle less than ninety degrees to the shoulders 6, 6, so that a force applied to increase the distance between the shoulders tends to distort the metallic strips and bring them nearer to a right angle with the shoulders. This distortion is illustrated by the dotted position of one end of the plate in Fig. 2. Permanent distortion is opposed by the resilient force in the metal strips.

As stated above, the distance between the shoulders, when the plate is free from the rail, is slightly less than the width of the rail base. As a consequence, when the rail is forced down to a seat between the shoulders as the plate is distorted as described, and the edges of the rail base are gripped by the shoulders with a force equal to the resilience of the metal.

The tie plate may be attached to the tie by any desired method, although I have only illustrated a preferred form of attachment wherein the same spikes used to hold the rail are passed through holes 12, 12 in the plate.

While I may depend upon a friction contact between the shoulders and the edges of the rail base to give a sufficient holding grip on the rail to prevent "creeping", yet I prefer to provide on the inner and rail-facing sides of the shoulders a series of sharp ridges 13, 13, adapted to indent the edges of the rail base. These ridges gradually wear into the rail base and are held in position by the contraction of the distorted plate reducing the space between the shoulders.

The principal novel feature of my present invention consists in providing a combined anti-creeping clamp and railway tie plate with a resilient, expandable construction in that portion which lies between or connects two shoulders adapted to bear against and grip the opposite edges of the rail base; the

construction being such that the distance between the shoulders is expanded to permit the seating of the rail.

Having thus described my invention, what I claim as new, and desire to secure by Letters Patent, is:—

1. An anti-creeping device for railway rails having shoulders for gripping the opposite edges of the rail base and an elastic connecting portion between said shoulders that is expansible by distortion.

2. An anti-creeping device for railway rails formed of resilient, wrought metal and comprising a clamp having integral shoulders with a seat between said shoulders narrower than the rail base and a resilient, expansible portion in the part of the device connecting said shoulders, whereby the rail base can be mechanically forced to its seat between said shoulders and be securely gripped thereby.

3. A railway tie-plate of wrought metal having shoulders for gripping the opposite edges of the rail base and an elastic portion connecting said shoulders that is expansible by the distortion of the metal.

4. A railway tie-plate having integral shoulders arranged to bear against the edges of the rail base with a seating space between said shoulders slightly narrower than the rail base and a resilient, expansible portion in the part of the plate connecting said shoulders, whereby the rail base is securely gripped when forced between said shoulders.

5. A one-piece railway tie-plate formed of resilient metal and adapted to be interposed between the rail and the tie and to be secured

to the tie, said plate having integral shoulders for gripping the opposite edges of the rail base with a seat between said shoulders narrower than the rail base, the part of the plate intermediate said shoulders being mechanically expansible by the distortion of the metal to permit the forcible seating of the rail-base between said shoulders.

6. A railway tie plate having shoulders with a seating space between said shoulders narrower than the rail piece and a resilient, expansible portion connecting said shoulders, whereby the rail base is securely gripped when forced between said shoulders, the inner faces of said shoulders being provided with gripping teeth.

7. A railway tie-plate having shoulders for engaging the opposite edges of the rail base, a part of the plate between said shoulders being divided by cuts or openings into a number of strips inclined at an angle to said shoulder, whereby the distance between said shoulders may be increased by a bending or distortion of said strips.

8. An anti-creeping device for railway rails formed of wrought metal, having shoulders with a seating space between said shoulders narrower than the rail-base and a resilient, yielding portion between said shoulders that is expansible by the distortion of the metal, whereby the rail-base may be forced to its seat between said shoulders and be securely gripped thereby.
